ACTIVATED DISPLAY DEVICE

George Thiberg, New York, N. Y., assignor of one-half to David Miller, New York, N. Y.

Application May 9, 1938, Serial No. 272,545

13 Claims. (Cl. 40—126)

This invention relates to improvements in display devices for advertising purposes.

Broadly, it is an object of my invention to provide a display device which will give the appearance of the bubbling or effervescence of many known beverages, tablets and pills that discharge gasses when brought in contact with liquids.

More particularly, it is an object of my invention to provide an aerator or air pressure device for use with advertising displays for drinks of various types or drinks mixed with other liquids, such as liquors, or mixed with sparkling or carbonated soda and ginger ales, etc., to simulate the rising bubbles known to such liquids or medical compounds.

A further object of my invention is to provide a display device having a recircularization of air. A further object of my invention is to provide a display device having a closed container for the fluid to prevent evaporation, overflowing, and the possibility of dirt and dust entering the container and fluid.

Heretofore, devices have been known for display purposes for liquids, which have open tops so that the fluid has to be constantly replaced or added because of evaporation. If alcoholic beverages are used, such as beer, a "head" or foam is created which overruns the top of the container causing loss of the beer and soiling of the display device. The open container causes germs, dirt and dust to collect, causing the parts, such as valves or any porous material, to become clogged, necessitating constant cleaning and replacement of parts. My device eliminates such defects.

Another object of my invention is to provide a display device having light, color, movement and interest, all necessary to good advertising displays. My device, therefore, makes provision for lighting and the other requisites.

These and other objects, advantages and capabilities will become apparent from the following detailed description when read in connection with the accompanying drawings, in which:

Fig. 1 is a perspective view of my display device, parts being broken away to show certain features of the invention.

Fig. 2 is an enlarged section taken on line 2—2 of Fig. 1.

Fig. 3 is taken on line 3—3 of Fig. 2.

Fig. 4 is a bottom elevational view of the compressor.

Fig. 5 is taken on line 7—7 of Fig. 2.

Referring to the drawings, reference numeral

10 represents a display device, having a base 12 in the form of a container. On the upper member 11 of base 12, there is mounted an inverted glass container 13. Within the base 12 and on the bottom wall 14 of the base 12, there is mounted an electric socket 15 to receive bulb 16 which may be of any desired color. Base 12 may have attached thereto background 17 for carrying out a sales display. The background 17 may be changed to take any desired shape and base 12 may take the shape of the package of the advertiser or any other desired shape. At the same time, it can be used to conceal the necessary parts, such as the electric bulb and socket, the base of the glass container and any other necessary working parts.

The glass container 13 has a shoulder 18, which rests upon upper member 11 of the base 12. The narrower lower portion 19 of container 13 projects into base 12 through an opening in upper member 11. Cover 20, having a rubber washer 21 covers the open bottom of container 13, and is attached preferably by a screw thread 22, or may be sealed with a vacuum cap (not shown). A vacuum thus created in container 13 will make easier pump action since the atmospheric pressure is eliminated.

Cover 20 has two openings through which are fastened an inlet member 23 and an outlet valve 24. Inlet member 23 has fastened to the upper portion a rubber tubing 25, upon which is mounted a block of porous material 26, which may be of carborundum, sandstone, pumice, silicon carbide, meerschaum, or similar material. A glass or Celluloid tubing 27, open at the top and extending just below the upper part of the glass container 13, is attached to outlet valve 24 by rubber tubing 28.

Inlet member 23 and outlet valve 24 are attached to a plate 28. A plate 29 is separated from plate 28 by a fibre ring 30 forming a compartment 31. Within compartment 31, there is a valve 32 through which air is forced into compartment 31. Another fibre ring 32 has attached to its lower part an inverted U-shaped plate 33 having a central opening 34 through which a laminated core 35 passes. By using a laminated core, eddy currents will be prevented and the unit will not become excessively overheated.

A rubber diaphragm 36 is held in position upon core 35 between upper washer 37 and lower washer 38 by screw 40. A cushion of soft rubber 39 is mounted below washer 38 to absorb the shock of the movement of core 35.

The rubber diaphragm 36 is held in position

between plate 29 and fibre ring 32 by screws 41 so that an air compartment 42 is created.

Attached to plate 33 by screws 43 is a U-shaped core 44 having a sleeve 45. In the center 5 of sleeve 45 there is a screw 46 having a cap 47 and a stop 48 for adjustment of the laminated core 35.

Plate 33 and U-shaped core 44 have slots 49 and 50, respectively, to prevent eddy currents 10 and keep plate 33 and core 44 from becoming excessively heated.

Between core 44 and laminated core 35 there 15 is an electric coil 51. Spacing exists between electric coil 51 and the sides of laminated core 35 and between the bottom of core 35 and stop 48 to allow for vertical movement of core 35 as indicated by the arrow in Fig. 2.

By passing an electric current through electric coil 51, laminated core 35 moves vertically 20 upward and downward, causing rubber diaphragm 36 to force air from compartment 42 through valve 52 into compartment 31. When air is forced through valve 52, it raises the washer 54 permitting the air to pass through wire mesh 25 55 into compartment 31. The wire mesh 55 limits the movement of the washer 54. The air thence passes through opening 53 and through the passage in inlet member 23 and rubber tubing 25 and through the pores of the porous material 26. The air thus forced through the porous material 26 rises through the fluid in glass container 13 and then rises to the top of the container, entering the glass or Celluloid tubing 27, returning through outlet valve 24 and compartment connecting tube 56 and into compartment 42 again to repeat its cycle. It will thus be seen that compartment 42 is both a compression and a suction chamber.

It is obvious that various changes and modifications 40 may be made in the details of construction without departing from the general spirit of the invention, as set forth in the appended claims.

I claim:

1. A display device comprising an inverted 45 transparent container for fluids, inlet and outlet means at the base of said container, a porous block within said container at said inlet, a tube having an opening at the top and leading to the top of said container and connected to said outlet, gas circulating means for forcing said gas into said inlet and for recirculating said gas to produce a bubbling of the fluid within said container.

2. A display device comprising a transparent 55 closed container, a supply of liquid within said container, inlet and outlet means at the base of said container, a porous block mounted on said inlet within said container, means for forcing a continuous supply of gas into said inlet and means for conducting said gas through said outlet back to the gas supplying means.

3. A display device comprising a transparent 65 closed container for fluids, inlet and outlet means to said container, a porous block upon said inlet means within said container, means for forcing gas into said inlet to create bubbles in the fluid, and means for returning said gas to the second mentioned means for recirculating said gas and sealing means to form a closed gas circulating system.

4. A display device comprising a transparent 70 container for fluids, inlet and outlet means for gas at the base of said container, porous material at said inlet and a tube at said outlet

within said container, an opening at the top of said tube, an electric pump for continuously circulating said gas through said inlet to be returned through said outlet whereby a bubbling is obtained of said fluid within said container. 5

5. A display device having a closed gas circuit, comprising a container for liquids, inlet and outlet valves at the base of said container, a porous material mounted upon said inlet and a tube having an opening at its top mounted upon 10 said outlet, an electrically operated core motivating a flexible diaphragm for compressing gas into said inlet and upon return of said gas to recirculate said gas whereby rising bubbles are formed in said liquid. 15

6. A display device comprising a transparent closed container, a liquid within said container inlet and outlet valves at the base of said container, a porous block attached to said inlet within said container, a tube having an opening at the top attached to said outlet, and means for pumping gas into said inlet, said gas returning to said pumping means through said tube and said outlet to be recirculated. 20

7. A display device comprising a transparent closed container, a liquid supply within said container, a supply of gas, an inlet and outlet at the base of said container, means for pumping said gas into said inlet, a porous material attached to said inlet within said container, a tube having an opening at the top and attached to said outlet within said container for returning said gas for recirculation. 30

8. A display device for bubbling liquids comprising a closed transparent container, said container having a shoulder near its base for seating upon a surface, a cap at the base of said container, inlet and outlet valves for said container mounted upon said cap, a porous material mounted upon said inlet valve within said container and a tube having an opening at the top mounted upon said outlet, means for continuously circulating gas through said inlet and said outlet whereby rising bubbles are formed in the liquid within said container. 35

9. A display device comprising a closed container for liquids, an inlet valve and an outlet valve leading to and from said container, a porous material attached to said inlet valve, a tube having an opening at the top attached to said outlet valve, an electric pump for motivating a flexible diaphragm for compressing gas into said container whereby bubbles are caused to rise and the gas to return through said tube and outlet valve to be recirculated. 50

10. A display device of the character described, comprising a closed container for a liquid, a source of gas under pressure, a porous material within said container, a tube having an opening within said container leading to an outlet valve, said outlet valve leading to said source of gas under pressure to again be recirculated. 60

11. A display device comprising a closed container for a liquid, a base for said container, an inlet member and an outlet valve leading to and from said container and attached to said base, said inlet member leading into a gas chamber, an inlet valve within said gas chamber, said outlet valve leading into a compression chamber, formed by a flexible diaphragm, a porous material mounted upon said inlet member, an electrically motivated moveable core attached to said diaphragm whereby upon movement of said core, gas is forced into said container through said porous material and the liquid within said 70

75

container, said gas returning through said outlet valve into said compression chamber.

12. In combination within a display device, a pumping device comprising a core, a threaded sleeve, an adjusting screw within said sleeve, an electric coil mounted upon said sleeve, a moveable reciprocating armature within said electric coil, a flexible diaphragm mounted upon an end of said armature, said flexible diaphragm attached to a plate forming a compression chamber, inlet and outlet valves leading to and from said display device for circulating a supply of gas within said container.

13. A display device comprising a support for an inverted transparent container for fluids, a shoulder at the base of said container for seat-

ing upon said support, a cap sealing the base of said container, gas inlet and outlet means mounted upon said cap, a porous block within said container mounted upon said inlet, a tube within said container extending to the top and having an opening at the top mounted upon said outlet, a compression and suction chamber formed by a flexible diaphragm, a reciprocating armature attached to said diaphragm, means for regulating the movement of said armature, whereby upon movement of said armature, gas is forced into said inlet and through said porous material causing a bubbling of the fluid within the container and upon return of said gas it is recirculated within the closed circuit.

GEORGE THIBERG.
